D. S. COE

MULTIPLE FORM SAFETY DEVICE

Filed Nov. 27, 1922

Inventor:

Demas S. Coe;

By Robert M. Kandell

Attorney.

Patented Nov. 20, 1923.

1,474,663

UNITED STATES PATENT OFFICE.

DEMAS S. COE, OF RICHMOND, INDIANA.

MULTIPLE-FORM SAFETY DEVICE.

Application filed November 27, 1922. Serial No. 603,493.

To all whom it may concern:

Be it known that I, DEMAS S. COE, a citizen of the United States, residing in the city of Richmond, in the county of Wayne, State 5 of Indiana, have invented a new and useful Multiple-Form Safety Device, of which the following is a full, clear, and exact description, the same being such as will enable others to make and use the same with exacti- 10 tude.

Modern business requires that billing, and certain kinds of recording, be done in multiple, that is there be a plurality of sheets or cards made out in identical form with relation to each other and having the same number indicative thereof.

However the objection to these multiple forms has been that the numbers become mixed and each sheet or card has to be examined separately to assure the numbers being correct, and frequently an incorrect number or sheet is not noticed until an entry has been made thereon, thereby causing confusion with consequent loss of time and material in correcting the same.

Therefore the primal object of this invention is to provide means whereby a person may instantly determine the correctness of the arrangement of the several sheets 30 without turning each sheet separately, in fact without even touching any of the sheets, thereby eliminating danger of error and facilitating the work of the operator.

Other objects and particular advantages 35 of my invention will suggest themselves in the course of the following description.

The preferred means for carrying out the principles of my invention in a practical manner is shown in the accompanying drawings, in which—Figure 1 is a face of a tablet containing a set of sheets to be used for a single transaction. Figure 2 shows the first sheet of the set turned to expose the second sheet. Figure 3 shows the second sheet 45 turned to expose the third sheet. Figure 4 shows the third sheet turned to expose the fourth sheet. And Figure 5 shows the fourth sheet turned exposing the fifth sheet of the set.

Similar indices denote like parts throughout the several views.

In this instance I have shown five sheets in each set or tablet, but I am not to be limited thereto, as there may be a greater or 55 a less number of sheets in each set.

In order that the construction, the opera-

tion, and the advantages of the invention may be more fully understood and appreciated I will now take up a detailed description thereof, in which I will set forth the 60 same as fully and as clearly as I may.

Referring now to the drawings in detail: Numerals 1, 2, 3, 4 and 5 denote the five sheets of paper forming a set, which are identical with each other in dimensions and 65 with relation to the printed matter thereon, the same to be filled in with identical data, either by carbon sheets or otherwise, preferably by means whereby all of the sheets are filled in at one operation, as by means of a 70 type-writing machine.

In this instance five oblong figures 6, 7, 8, 9 and 10 are printed across the upper portions of the respective sheets 1, 2, 3, 4 and 5, it of course being understood that the number of said figures should be the same as the number of sheets in any one set or tablet.

Each sheet is provided with but one permanent identification number, which numbers must be the same in all of the sheets of any one set, which identification number in this instance I have arbitrarily given as "4850," and which are referred to herein simply as identification numbers 11, 12, 13, 85 14 and 15, for the respective sheets 1, 2, 3, 4 and 5.

Identification number 11 is printed upon sheet 1 within the first oblong figure 6 at the right, while the material of sheet 1 within the other four figures 6 are cut-away forming the four apertures 16, which are concentric with their respective figures 6, substantially as shown in Fig. 1.

Identification number 12 is printed upon sheet 2, within the second oblong figure 7 from the right, while the material of sheet 2 within the other three oblong figures 7 to the left thereof are cut-away forming the three oblong apertures 17, while the space within the oblong figure 7 at the right remains blank, all substantially as shown in Figure 2 of the drawings.

Identification number 13 is printed upon sheet 3, within the central oblong figure 8, while the material of sheet 3 within the other two oblong figures 8 to the left thereof are cut-away forming the two apertures 18, while the space within the two oblong figures 8 at the right simply remain blank, as 110 shown in Fig. 3.

Identification numeral 14 is printed upon

sheet 4, within the oblong figure 9 next to the left, while the material of sheet 4 within the left-hand oblong figure 9 is cut-away forming the aperture 19, while the spaces 5 within the oblong figures 9 at the right simply remain blank, as shown in Fig. 4.

Identification numeral 15 is printed upon sheet 5, within the left-hand oblong figure 10, while the other four oblong figures 10 10 simply remain blank, there being no aperture formed through sheet 5, as indicated in Fig. 5.

The five sheets forming a set or tablet may be secured together as at the left by the 15 clip 20, as shown in Fig. 1, or they may be secured in any other manner whereby the marginal edges of all of the sheets in the set will be even with each other.

When the five sheets are secured together 20 it is evident that each of the oblong figures 6 will be directly above the respective oblong figures 7, 8, 9 and 10, whereby the aperture 16 at the left will register with the apertures 17, 18 and 19 at the left, by reason of 25 which the numeral 15 of sheet 5 can be seen through all of said apertures at the left. Likewise the second aperture 16 from the left will register with the second apertures 17 and 18, from the left, by reason of which 30 the numeral 14 of sheet 4 can be seen through apertures 16, 17 and 18.

Likewise the third aperture 16 from the left, will register with the third aperture 17 from the left, by reason of which the 35 numeral 13 of sheet 3 can be seen through said apertures 16 and 17.

Likewise the numeral 12 of sheet 2 can be seen through the fourth aperture from the left of sheet 1. And of course numeral 11 40 of sheet 1 can be seen directly upon said sheet 1, as in Fig. 1.

It is now evident that when a tablet or set of associate sheets are laid flat, as in Fig. 1, a single glance will show that the identifying 45 numerals, as 4850, is the same on each of the sheets.

The operator may now place a carbon sheet between each two of said sheets of the set and the name of the customer, date, 50 and other data, together with the information to be recorded may be entered upon sheet 1 whereby the same matter will be transmitted to the other four sheets of that set, after which the sheets may be separated and one 55 given to the customer, one filed as a permanent record, and the others used for various purposes such as is customary in certain lines of business especially in large establishments.

It is also to be understood that this invention is adapted to be used in connection with sets of cards or the like, to be used by banks or installment concerns, wherein one or more cards of a set bearing a certain identifying character is held by the issuing concern, and another card bearing the same identifying character is to be held by the patron and presented at the time of each payment, and when the cards bearing the same identifying characters are placed together, one above the other the identifying characters of all will be visible, the identifying character of the under card being visible through an aperture in the upper card or cards, thereby not only assuring that the cards are of the same set, but thereby aligning the cards whereby the punching of an amount, or other data, may be made on both or all of the cards of the set at one and the same time and with one operation.

I desire that various changes may be made in the several details herein set forth without departing from the spirit of the invention and without sacrificing any of the advantages thereof which are new and useful 85 and which involve invention.

Having now fully shown and described my invention, what I claim and desire to secure by Letters Patent of the United States, is—

1. Multiple billing and record forms comprising a plurality of superposed sheets connected together, each of said sheets having a permanent number printed thereon all of said numbers being identical with each other, means whereby the numbers of each of the sheets may be seen at one time without turning any of the sheets.

2. A plurality of superposed sheets containing printed matter and data which is identical with each other, and each sheet having an identifying mark thereon all identical with each other, and means whereby all of said identifying marks can be seen at one time without turning any of the sheets 105 or disarranging the alignment thereof.

In testimony whereof I have hereunto subscribed my name.

DEMAS S. COE.
